CLAIM

The ornamental design for an operating unit for surgical device, as shown and described.

DESCRIPTION

FIG. 1 is a top, and front, right-side perspective view of an embodiment of an operating unit for surgical device showing our new design.

FIG. 2 is top, and front, left-side perspective view thereof;

FIG. 3 is a front view thereof, a rear view being a mirror image of FIG. 3;

FIG. 4 is a top view thereof;

FIG. 5 is a bottom view thereof;

FIG. 6 is a left side view thereof; and,

FIG. 7 is a right side view thereof.

The broken lines shown in the drawings illustrate portions of the operating unit for surgical device that form no part of the claimed design.
